UNITED STATES PATENT OFFICE.

JOHN DOONER, OF CHICAGO, ILLINOIS.

OIL-FILTERING APPARATUS.

SPECIFICATION forming part of Letters Patent No. 429,340, dated June 3, 1890.

Application filed June 20, 1889. Serial No. 314,915. (No model.)

To all whom it may concern:

Be it known that I, JOHN DOONER, a citizen of the United States, residing at Chicago, in the county of Cook and State of Illinois, have invented certain new and useful Improvements in Oil-Filtering Apparatus, of which I do declare the following to be a full, clear, and exact description, reference being had to the accompanying drawings, forming part of this specification.

My present invention has for its object to provide improved mechanism whereby low-grade or impure lubricating-oil may be filtered and purified before its use, and whereby also lubricating-oil that has been used and has thereby accumulated more or less impurities incident to use can be purified, so that it may be used over and over again for lubricating purposes. This object of invention I have accomplished by the novel features of construction hereinafter described, illustrated in the accompanying drawings, and particularly pointed out in the claims at the end of this specification.

Figure 1 is a perspective view of a purifying apparatus embodying my invention. Fig. 2 is an enlarged view partly in perspective and partly in central vertical section through my improved apparatus.

In the preferred embodiment of my invention there are four tanks, designated, respectively, A, B, C, and D, the tanks A and B being sustained above the tank C by means of suitable uprights or standards 2 of convenient construction. The tank A, which is shown as of cylindrical shape, is provided at its top with a removable cover a, that is preferably furnished with a supplemental lid or cover a', and in the bottom of this tank is located a heating-coil 3, that receives steam from a steam-pipe 4, a globe-valve 5 serving to control the admission of steam to the coil 3 and a similar valve 6 serving to control the escape of the steam into the waste-pipe 7, and consequently to regulate the pressure and temperature of the steam within the tank A. From the main delivery steam-pipe 4 also extends a steam-pipe 10, the lower end of which is connected with a bend or coil 11, located within the bottom of the tank B, this bend or coil being also connected with an escape-pipe 12, that connects with a coil 13, that is located

within the bottom of the tank C. The delivery of steam through the pipe 10, the coil 11, the pipe 12, and the coil 13 is controlled by a suitable valve 14 in the main steam-delivery pipe 4, and the escape of steam and consequently the temperature and pressure of steam within the tanks B and C is controlled by the valve 15 in the pipe that connects the coil 13 with the main waste-pipe 16, to which waste-pipe also the waste-pipe 7 is connected.

From this construction it will be seen that the temperature within each of the tanks A, B, and C can be regulated, for the purposes to be hereinafter stated. The tank A is provided with suitable escape-cocks, (three of such cocks, designated as F, G, and H, being shown in the drawings,) and from beneath each of these cocks leads a branch pipe 20, which serves to deliver the oil into a main pipe H', that discharges into the top of the tank B. Within this tank B is placed a series of riffle plates or trays b, in any desired number, (five being shown in the drawings,) these trays being provided with transverse bars or riffles b', and being inclined in opposite direction, so that the oil delivered at one end of the top plate of the series shall flow over each of the succeeding plates before its final delivery into the lower portion of the tank B. The top of the tank B is provided with a removable cover B', which may be lifted off when it is necessary to withdraw the riffle-plates for the purpose of cleaning them, and by preference, also, this cover B' is furnished with a supplemental lid or cover B'', which can be lifted from time to time to permit the engineer to inspect the condition of the plates. In the lower portion of the tank B is placed a discharge-cock K, from which leads the pipe L, that serves to conduct the oil from the tank B to the top of the tank C. The top of the tank C is provided with a removable cover C', which can be withdrawn from time to time when it is necessary to remove the filter from the tank C for the purpose of cleaning or renewing it, and by preference, also, the cover C' is furnished with one or more supplemental lids or covers C'', through which the engineer can inspect the condition of the filter within the tank C. The pipe L leads into the cover C' of the tank C, immediately above a funnel-shaped filter M, that is connected to

the upper end of the pipe *m*, that extends down to a point adjacent the bottom of the tank C, and upon this pipe *m* is fixed the filter O. This filter O consists, preferably, of the upper and lower perforated plates or screens *o* and *o'* and the intermediate packing of moss, palm-leaf, or the like, these perforated plates or screens *o* and *o'* serving to retain the packing in proper position. In the upper portion of the tank C is placed an escape-cock P, which serves to deliver the oil through the top of the tank D. This tank D is by preference divided into the two compartments R and R', the compartment R being furnished with an inclined screen S, upon which the oil will be delivered as it passes through the escape-cock P. The partition-wall *r*, that divides the tank D into the compartments R and R', is cut away at its bottom and a screen S' there placed serves to separate the lower portions of the two chambers of this tank. The upper portion of the tank D is provided with the hinged lids or covers D', which can be lifted from time to time to permit the cleaning of the tanks when necessary. Each of the tanks A, B, and C is furnished at its bottom with a waste-cock 30, that serves to conduct away the water that accumulates within the tank to the drain-pipe W.

From the construction of parts as above defined, the operation of my improved apparatus will be seen to be as follows: The impure oil, either low-grade oil that has not been used or oil that has been collected after use upon the shafting, engine, or other machinery, is placed in the tank A, and steam is then admitted through the main steam-pipe 4 to the heating-coil 3 within the bottom of this tank, the admission and escape of the steam being controlled by the valves 5 and 6. The oil will be allowed to slowly boil within the tank A for about two hours, more or less, according to its gravity and the amount of impurities contained therein, care being taken that it does not boil over, and after the boiling is completed it should be allowed to stand for six hours, more or less, until the impurities settle. The cocks F, G, and H will then be successively opened and the oil will be allowed to pass through the pipe H' onto the riffle-plates *b* within the tank B. If, on opening the cock H, it should be found that water escapes through such cock, then the escape-cock 30 should be opened to permit the water to escape until the body of oil falls below the level of the cock H. By the boiling operation within the tank A it will be found that the oil has been freed in great measure from much of its impurity, and as it passes slowly down the series of riffle-plates within the tank B the transverse bars or riffles *b'* of these plates will serve to further arrest and collect the impurities from the oil before it finally passes into the lower portion of this tank B. If desired, the tank B may be heated by turning the cocks 14 and 15 in such manner as to

permit the passage of steam from the main steam-pipe 4 through the coil or bend 11 within the bottom of this tank. By opening the cock K in the lower portion of the tank B the oil will be next conducted into the pipe L through the cover C' of the tank C and into the filtering-funnel M within this tank. This filtering-funnel M will aid in further removing the impurities from the oil, after which it will pass by the pipe *m* to the bottom of the tank C, when it will rise through the body of water in the bottom of the tank and up through the perforated plates *o* and *o'*, and the intermediate packing of moss or palm leaf, until it reaches the upper portion of the tank. The water and oil within the tank C will be heated during this operation by the steam-coil 13. From the upper portion of the tank C the oil, now freed in great measure from its impurities, will be delivered through the escape-cock P into the top of the chamber R of the tank D, and will fall upon the screen S before passing to the bottom of this chamber. From the bottom of the chamber R the oil will pass through the screen S' into the bottom of the chamber R', from which chamber it may be drawn off from time to time as needed for use through the cocks 26, 27, and 28. The tank D is furnished at its bottom with a waste-cock 40, which will serve to withdraw from the tank when necessary the water and impurities collected therein.

The tanks A, B, C, and D may be constructed of any suitable material, although I prefer galvanized iron for the tanks A, B, and C and heavy block-tin for the tank D.

When it is desired to clean the tanks, the pipe H', that connects the tank A with the tank B, will be disconnected, so that the cover of the tank B can be removed to permit the withdrawal of the riffle-plates therefrom, and in like manner the pipe L, that connects the tank B with the tank C, can be disconnected in order to permit the cover C' of the tank C to be lifted off, so that the filter O can be withdrawn when the tank is to be cleaned or a new filter is to be substituted.

Having thus described my invention, what I claim as new, and desire to secure by Letters Patent, is—

1. In an oil-filtering apparatus, the combination of a tank A, provided with a steam-heating pipe, whereby the boiling of the impure oil within the tank may be effected, and provided with a discharge-cock for oil at a distance above its bottom and a waste-cock for sediment and the like at its bottom, and a tank B, arranged beneath said tank A and having a pipe leading thereto from the discharge-cock of the tank A at a distance above its bottom, whereby the partially-purified oil may be withdrawn from the tank A to be further purified within the tank B, while the impurities resulting from the boiling of the oil may be withdrawn from the bottom of the tank A and be prevented from passing into the tank B, substantially as described.

2. In an oil-filtering apparatus, the combination of a tank A, provided with a steam-heating pipe, whereby the boiling of the oil within the tank may be effected, and provided with a discharge-cock for oil at a distance above its bottom and a waste-cock for sediment or the like at its bottom, and a tank B, provided with riffle-plates and with a heating-coil, and a suitable pipe connecting said tanks A and B, whereby the oil, after having been

boiled and allowed to settle within the tank A, may be withdrawn into tank B and passed over the riffle-plates sufficiently reheated to secure the desired fluidity, substantially as described.

JOHN DOONER.
